UNITED STATES PATENT OFFICE.

CHARLES E. WAREAM AND ALBERT J. DREHER, OF NORWOOD, OHIO, ASSIGNORS TO THE AMERICAN LAUNDRY MACHINERY COMPANY, OF NORWOOD, OHIO, A CORPORATION OF OHIO.

PRESSING MACHINE.

Application filed August 30, 1919. Serial No. 320,929.

To all whom it may concern:

Be it known that we, CHARLES E. WAREAM and ALBERT J. DREHER, citizens of the United States, residing at Norwood, in the county of Hamilton and State of Ohio, have invented certain new and useful Improvements in Pressing Machines, of which the following is a specification.

This invention relates to pressing machines, and more particularly to what are known as small presses, such as are used for pressing cuffs and neckbands of shirts or other parts of wearing apparel.

The object of the invention is to provide improved operating mechanism for producing relative movement between the pressing members, and more specifically improved operating mechanism so arranged as to permit the pressing members to be moved part way toward each other by foot power and thereafter brought into pressing relation under heavier pressure by power means controlled by the operating of the foot treadle or other operating part.

A further object of the invention is to provide cylinder and piston mechanism for producing heavy pressure between the pressing members, the flow of fluid pressure, such as steam, to the cylinder being controlled by the same operating member which produces relative movement of the pressing members.

A further object of the invention is to provide steam actuated mechanism for producing relative movement between the pressing members, the arrangement being such that the steam for actuating said members also heats the lower member or bed and thereby avoids condensation of moisture in its padded surface.

A further object of the invention is to provide improved means for carrying away or discharging from the machine any moisture or condensed steam which otherwise might collect in or around the cylinder and piston mechanism.

A further object of the invention is to generally simplify and improve the mechanism so as to provide a strong, powerful, and durable machine at minimum cost.

Further objects of the invention are in

part obvious and in part will appear more in detail hereinafter.

In the drawings, which represent one suitable embodiment of the invention, Fig. 1 is a front elevation showing the press in open position, part of the frame being broken away and in section; Fig. 2 is a rear elevation; Fig. 3 is a side elevation, parts of the frame being broken away and in section on the line 3-3, Fig. 1, to expose interior parts; Fig. 4 is a detail sectional elevation of the controlling valve mechanism, on the line 4-4, Fig. 5, the operating devices therefor being shown in elevation; Fig. 5 is a sectional elevation of the power operating mechanism, the section being taken on the line 3-3, Fig. 1; Fig. 6 is a sectional elevation of the power operating mechanism, on the line 6-6, Fig. 5; Fig. 7 is a horizontal section on the line 7-7, Fig. 6; Fig. 8 is a sectional plan view on the line 8-8, Fig. 3; and Fig. 9 is a detail view of a bell crank lever, the view being a section on the line 9-9, Fig. 3.

The machine shown in the drawings comprises a suitable frame or housing 1 adapted to rest upon the floor or other suitable support and provided with a hollow base 2 and upright pillars 3 which support the hollow upper pressing member or head 4, which may be of any suitable form and is preferably heated by supplying steam to or circulating it through its chamber 5 in the usual manner in such machines. Below the head is mounted a cooperating bed 6, which is vertically movable to enable it to be brought into or moved away from the pressing relation with the head. This bed preferably is provided with a padded work support 7 slidable horizontally upon said bed 6, and carried by a rod 8 movable through said bed and provided on its outer end with a handle 9. This arrangement enables the padded work support 7 to be pulled out from registry with the head for applying the work to or removing it from the work support. A tension spring 10, connected at one end to a suitable stationary support and at its other end to a lever 11 pivoted at 12 to a bracket on the frame and at its upper end having a vertical slot 13 to

receive a pin 14 on the rod 8, always tends to move the work support away from the position shown in Fig. 5, to a position in which said support is out of registering relation with the bed.

Suitable means is provided for enabling the operator to elevate the bed toward the head. The means shown comprises a foot treadle 15 pivoted at 16 to the stationary base and having an arm 17 serving as one member of a toggle, said arm being pivotally connected at 18 to the other toggle member 19 which is provided with a U-shaped yoke portion 20 the slot of which receives a pin 21 on a yoke 22, whose opposite ends extend out beyond the frame, as shown in Fig. 1, and are connected to rods 23 sliding vertically in guiding portions 24 of the frame. Said rods at their upper ends are connected by knuckles 25 to rods 26 rigid with the bed member 6.

By depressing the treadle 15 the toggle 17, 19 is closed and the bed elevated toward the head, but this treadle motion does not bring the pressing members into pressing contact. The relative motion of the pressing members is slow so that the operator always has time to remove his fingers from the bed if he chances to be holding or arranging the work thereon.

In the upper position of the bed the toggle pivot 18 is moved slightly beyond a straight line joining the pivots 16, 21, as is usual. Consequently, the machine is provided with suitable releasing means for breaking the toggle, such as the release treadle 27 pivoted at 28 and having an arm 29 lying beneath the treadle 15. By depressing the release treadle the pressure treadle 15 is elevated and the toggle broken.

The bed 6 is in one piece with or is carried by a hollow cylinder 30 closed at its lower end by a cap 31. Said cylinder and cap, together with the bed 6 supported thereby, have vertical sliding motion relative to a piston 32, which lies within the cylinder and is supported at the upper end of a hollow piston rod 33. Said rod is supported at its lower end by a hollow base 34 suitably mounted rigidly upon the frame, such as by the provision of feet 35 which are bolted to a cross member of the housing, as shown in Fig. 6. To one side of said base is connected the hollow extension 36 of a valve casing 37, the valve mechanism whereof controls the flow of fluid pressure to and from the cylinder.

38 represents the fluid pressure supply pipe connected to any suitable source of pressure, preferably steam, while 39 represents the outlet through which the used steam is discharged to any suitable point. The fluid pressure supplied through the pipe 38 flows to an admission chamber 40 in the valve casing and thence through a port

41 to a chamber 42, the flow to said chamber being regulated by an adjustable needle valve 43 whose stem 44 extends to the outside of the valve casing for adjustment thereof.

In the chamber 42 is a valve 45 (Fig. 4) seating downwardly and adapted to close a port 46 leading to a chamber 47. Stem 48 of said valve extends upwardly through a suitable packing and is connected by a link 49 to one arm of a lever 50 pivoted at 51 to a suitable bracket 52 on the stationary frame. In chamber 47 is a similar valve 53 seating downwardly and adapted to close a port 54 leading to the discharge chamber 55 with which the pipe 39 communicates. The stem 56 of said valve extends upwardly through a suitable packing and is connected by a link 57 to the other arm of lever 50.

Chamber 47 communicates with a passage 58 in the extension 36, said passage communicating with a vertical passage 59 in the hollow base 34 and piston rod 33. Said passages establish communication at all times between the chamber 47 and the chamber in the cylinder 30 above the piston therein.

The valve operating mechanism is as follows:

Lever 50 is connected at its outer end to a sleeve 60 slidable vertically upon a rod 61 and held between two compression springs 62 on said rod. The tension of said springs may be adjusted by more or less screwing up the nuts 63 which serve as abutments for the outer ends of the springs. Rod 61 is pivotally connected at its lower end to one of a lever 64 pivoted at 65 on the stationary frame, the other arm of said lever being connected by a link 66 to a portion of the treadle 15.

Let us assume that valve 43 is opened so that fluid pressure flows to the chamber 42, the parts being in the positions shown in the drawings with valve 45 closed and valve 53 open. Depression of the treadle 15, as before stated, advances the bed upwardly toward the head. At the same time the link 66 is pulled down and rod 61 is elevated. The pressure in chamber 42 maintains the valve 45 closed until the pressure of the lower spring 62 exceeds the pressure in chamber 42, whereupon lever 50 is suddenly turned in a clockwise direction (Fig. 4), thereby opening valve 45 and closing valve 53. The parts are so adjusted that this valve operation does not occur until the bed has almost reached the head and is so close to it in fact that the operator must have removed his fingers from between the pressing members.

When the valve operation occurs fluid pressure flows to chamber 47 and through the passages 58, 59 to the cylinder 30 thereby elevating said cylinder and the bed into close pressing relation with the head and applying heavy pressure to the work. During this additional upper

- movement of the bed the pin 21 slides upwardly through the slot in the yoke 20. Pressure on the work may be maintained as long as desirable. When a sufficient period 5 has elapsed the release treadle 27 is depressed and the pressure treadle 15 is thereby elevated. Toggle 17, 19 is immediately broken, the parts moving to the position shown in Fig. 3, but until the valve mechanism 10 again operates no downward movement of the pin 21 occurs. Elevation of the pressure treadle 15 raises the link 66 and pulls down the rod 61. Valve 53 is held to its seat by the pressure in chamber 47, so that 15 the valves do not move until the pressure of the upper spring 62 exceeds the pressure in chamber 47, whereupon the lever 50 is suddenly returned to its original position, valve 53 is opened and valve 45 is closed. 20 This valve operation cuts off communication from the source of supply to the hollow cylinder and establishes communication from the cylinder to the exhaust through the pipe 39. The parts are then ready for another 25 operation.

The joint between the engaging surfaces of the piston and cylinder is closed by the usual piston rings. However, some steam may pass this joint. Suitable 30 means is therefore provided for withdrawing the condensed moisture, and also for establishing communication from the chamber 67 beneath the piston and the atmosphere. The means shown comprises a 35 channel 68 in the piston 33 and base 34, and which channel communicates at one end with the chamber 67 and at its opposite end with a pipe 69 leading to the sewer.

With the arrangement described the steam 40 supplied for operation of the bed always keeps the bed hot, as a consequence of which the padded work supporting part never becomes cold enough to condense any moisture which may be in the work being 45 ironed. Consequently, the padded work support does not absorb moisture and remains dry. The press is of comparatively simple construction and uses the same source of steam for operating the pressing 50 members as for heating the same. It also enables heavy power pressure to be applied without liability of injuring the operator.

What we claim is:—

1. A pressing machine, comprising relatively movable pressing members, a stationary piston, a cooperating movable cylinder operatively connected to one of said members, a hollow piston rod through which fluid pressure is supplied to said cylinder 55 and a fluid supply means therefor, said cylinder providing a chamber surrounding said piston rod for receiving condensed moisture, and means for conducting said moisture away from said chamber.
2. A pressing machine, comprising relatively movable pressing members, a stationary piston, a cooperating movable cylinder operatively connected to one of said members, a hollow piston rod through which fluid pressure is supplied to said cylinder 60 and a fluid supply means therefor, said cylinder providing a chamber surrounding said piston rod for receiving condensed moisture, and means for conducting said moisture away from said chamber.

tively movable pressing members, a stationary piston, a cooperating movable cylinder operatively connected to one of said members, a hollow piston rod through which fluid pressure is supplied to said cylinder, 70 and a fluid supply means therefor, said cylinder providing a chamber surrounding said piston rod for receiving condensed moisture, said piston rod having a channel communicating with said chamber for withdrawing moisture therefrom.

3. A pressing machine, comprising a stationary piston, a movable cylinder cooperatively related thereto, means for supplying steam to said cylinder, a movable pressing member in heat conducting relation with said cylinder, a cooperating pressing member, a foot treadle for producing relative movement between said pressing members, and means controlled thereby for controlling the flow of steam to said cylinder. 80

4. A pressing machine comprising relatively movable cylinder and piston members, one of which is stationary, a work support in heat conducting relation with said cylinder, a pressing member co-operating therewith, means for effecting relative movement of said pressing members, and means controlled by said first named means for supplying steam to said cylinder. 95

5. A pressing machine, comprising a stationary frame supporting a fixed pressing member, a piston immovably supported by said frame, a pressure cylinder cooperating with said piston and movable relative to said stationary pressing member, a work support lying between said pressing member and cylinder and in heat conducting relation with said cylinder, a foot treadle for producing relative movement between said cylinder and pressing member, a steam supply means, and means actuated by said treadle for controlling the flow of steam to said cylinder. 100

6. A pressing machine, comprising a stationary frame supporting a fixed pressing member, a piston immovably supported by said frame, a pressure cylinder cooperating with said piston and movable relative to said stationary pressing member, a work support lying between said pressing member and cylinder and in heat conducting relation with said cylinder and movable relatively thereto into and out of position between said cylinder and pressing member, a foot treadle for producing relative movement between said cylinder and pressing member, a steam supply means, and means actuated by said treadle for controlling the flow of steam to said cylinder. 110

7. A pressing machine, comprising a stationary upper pressing member, a co-operating lower vertically movable pressing member, a work support horizontally movable thereon into and out of register. 120

ing relation with said pressing members, for such heating purposes and for also 10
operator-operated means for closing the
press, said lower pressing member includ-
ing relatively movable cylinder and piston
members, said cylinder member being so
arranged on the lower pressing member as
5 to heat the same and thereby heat a garment
upon the work support, and means for
supplying steam to said cylinder member

In testimony whereof we affix our signa- 15
tures.

CHARLES E. WAREAM.
ALBERT J. DREHER.
